UNITED STATES PATENT OFFICE.

NAASON Z. BUTTERICK, OF JACKSONVILLE, FLORIDA.

FLEXIBLE ROOF COVERING.

Application filed March 20, 1922. Serial No. 545,313.

To all whom it may concern:

Be it known that I, NAASON Z. BUTTERICK, a citizen of the United States, residing at Jacksonville, in the county of Duval and 5 State of Florida, have invented certain new and useful Improvements in Flexible Roof Coverings, of which the following is a specification.

This invention relates to roof coverings, 10 consisting of strips or elements adapted to be arranged in overlapping rows, the finished roof presenting an ornamental, attractive appearance.

The roofing elements or strips are prefer- 15 ably cut from a continuous sheet of treated fabric consisting of a fibrous body impregnated with a waterproof compound such as is ordinarily employed for the purpose and may be provided with an external layer of 20 weatherproof material. These strips may be cut or sheared from a continuous sheet of such material in such a manner that all of the material enters into the strips without waste.

25 Roof coverings have heretofore been constructed of strips cut from continuous sheets of weatherproof fabric and laid in overlapped relation to produce ornamental designs simulating shingles or tiles. In all 30 such cases, however, the strips were so cut or shaped that the resulting configuration presented an absolutely uniform design. While some of these designs are very attractive and were frequently relieved by the use 35 of contrasting colors or simulation of shadows here and there, yet, withal their appearance was more or less monotonous.

I have discovered a method of cutting the 40 roofing strips so that they may be laid in such a manner as to entirely break up the monotony above referred to and at the same time present the exceedingly attractive appearance of the well-known thatched roofs which were quite prevalent years ago in the 45 old country and which still delight the eye of the tourist who ventures from the beaten paths into the rural districts of England, Scotland and other countries. The eye never tires of the irregular wavy lines of the 50 thatched roof. One of the main purposes of my invention is to provide roofing strips which may be overlaid in such a manner that the exposed portions between adjacent curvi- 55 linear edges or margins of the strips present the irregular wavy configuration simulating the corresponding portions of a thatched

roof. By reason of the flexibility of these felt composition roofing strips, they may be carried or bent over the projecting edges of the roof in such a manner as to give the appearance of the usual thickness of a thatched roof. 60

In the following description, I shall refer to the accompanying drawings in which Figure 1 is a perspective view of a portion of a 65 roof having a covering embodying my invention; Fig. 2 is a top plan view of a portion of a roof showing the manner of overlapping the roofing strips; Fig. 3 is a trans- 70 verse sectional view on the line 3—3 of Fig. 2; and Fig. 4 is a bottom plan view of a portion of a roof showing the manner of overlapping the strips as it appears from underneath.

The roofing strips 5 are cut from sheets, 75 perhaps 40 feet long or even more, these sheets being first severed into strips substantially double the width of the finished strips and these are then cut through the central portion by longitudinal wavy lines of irregu- 80 lar curvature, each of the strips thus resulting in two finished roofing strips having one straight longitudinal edge and the opposite edge of irregular curvature.

In laying the strips upon the roof in over- 85 lapping relation, the adjacent strips are selected with their wavy edges all pointing downwardly or in the same direction and so chosen that the irregular curvilinear edges or margins of adjacent overlapping 90 strips will not be parallel. In other words, two identically formed strips are never laid adjacent each other or if they are so laid, one strip is slid longitudinally so that the cor- 95 responding curved margins will not be in alignment. It is sufficient to see that this does not occur at each end, since if they are not parallel at one point they will not be at any point throughout their length. Ob- 100 viously, the strips as a whole must overlap the same distance, this distance being regu- 105 lated by spacing the straight rear edges 5^a the same distance apart, as indicated in the rear or underneath plan view shown in Fig. 4.

When the strips are laid in the manner above described, the exposed portions between any two adjacent irregular wavy mar- 110 gins 5^b will present the undulating irregular wavy configuration, illustrated in the top plan view shown in Fig. 2. Those who are familiar with the thatched roofs frequently

found in the rural districts of the old countries, which are constructed of sod turf and straw, will appreciate the fact that these wavy undulating lines produced in the construction of my roof covering simulate very closely the appearance of such thatched roofs. This resemblance is carried out more completely by the manner in which my roofing strips can be curved or bent with greater 10 or less fullness over the ends and edges of the roofs so that they give the appearance of thickness, as I have endeavored to illustrate in the pictorial illustration shown in Fig. 1.

I have described in detail the particular 15 construction illustrated in the accompanying drawings, but it will be evident that various changes and modifications may be made within the spirit of my invention and without departing in any manner from the rights 20 which are covered in the following claims.

I claim:—

1. A roofing strip of uniform thickness formed of flexible weatherproofed fibrous

material and having one longitudinal edge or margin provided with serrations of irregular curvature so that when said strip is laid with others in overlapping rows with the serrations longitudinally displaced with respect to each other the exposed portions of the strip continuously vary in width, thereby 25 forming a band of irregular wavy configuration. 30

2. A roofing strip formed of flexible composition fibrous material having one straight longitudinal edge and the opposite edge provided with serrations of such curvature that when laid with others in overlapping rows with the serrations longitudinally displaced with respect to each other the portions of a strip exposed between adjacent curvilinear edges or margins continuously vary in width, thereby producing an irregular wavy configuration simulating the corresponding portions of a thatched roof. 40

In testimony whereof I affix my signature. 45
NAASON Z. BUTTERICK.
